UNITED STATES PATENT OFFICE.

JACOB A. CONOVER, OF NEW YORK, N. Y., ASSIGNOR TO ALBERT F. CHILDS,
OF WASHINGTON, DISTRICT OF COLUMBIA.

FORMER FOR TABLE-FRAMES.

SPECIFICATION forming part of Letters Patent No. 289,623, dated December 4, 1883.

Application filed August 29, 1883. (No model.)

To all whom it may concern:

Be it known that I, JACOB A. CONOVER, a citizen of the United States, and a resident of the city and State of New York, have invented 5 certain new and useful Improvements in Formers for Table-Frames; and I do hereby declare that the following is a full, clear, and exact description thereof, reference being had to the accompanying drawings, forming part of this 10 specification, in which—

Figure 1 is a plan view of the former. Fig. 2 is a plan view of the former and of the table-frame secured therein; Fig. 3, a section on the line *a a* of Fig. 2, and projection of parts beyond; Fig. 4, a section on the line *b b* of Fig. 2, and projection of parts beyond; Fig. 5, a plan view of extensible former; Fig. 6, a side elevation of same; Fig. 7, a section through the line *f f* of Fig. 5, and projection of parts 20 beyond; Fig. 8, a section through line *r r* of Fig. 5, and projection of parts beyond. Fig. 9 is a plan view of one of the corners of the former, showing the adjustable strip applied to the ends of two of the rails and clamped 25 thereto.

The object of my invention is to provide a former, by the employment of which the elements that compose the frame of the table may be secured in their proper positions and the 30 completed frame readily withdrawn from the former.

My invention consists, first, in a device comprehending a base supporting side pieces or standards, wherein the planes of the interior faces of two adjacent sides are respectively at obtuse angles with the plane of the base, and adjustable compensating wedge-pieces, 35 forming part of the former; second, in a former composed of four sections, each section comprising a base formed of two arms secured at 40 right angles to each other, each arm carrying a standard or a portion of a side of said former, and each section adjustable, its arms traveling on the upper surfaces of the rails of a sub-base, whereby the sections may be adjusted 45 to the positions desired.

In Figs. 1, 2, 3, and 4 the base of my former is composed of the bars *D D'*, to which is secured the cross-bars *C C'*. These bars are secured 50 to each other relative to the size of the table-frame to be made. Standards are erected

on and secured to these bars of a height commensurate with the width of the rail of the table-frame. The inward faces of the standards *A' A' B' B'* are preferably at right angles 55 with or perpendicularly to the plane of the base, and the standards *A A B B* have their inward faces presenting an obtuse angle with the floor of the base. Each contiguous pair of standards and the arms supporting them 60 at the corners of the base, as *A' B*, &c., are connected by the brace *E*, secured firmly to the bars. The wedge-pieces are compensating pieces—*i. e.*, are employed between the sides of the former and the rails of the frame— 65 by means of which wedge-pieces the configuration of the frame may be determined and said frame held in position until completed. The rails of the table-frame are placed in the former, as shown in Fig. 2. The rails *I I* are 70 first inserted, their outward faces in contact with the standards *B B* and *B' B'*, respectively. The ends of a narrow brace or prop, *n*, is then brought into engagement with the interior faces of the rails, in order to keep them temporarily in their places. The other rails, *J J*, are then inserted and the brace *m* inserted 75 to hold them in position. The corner-blocks *F* of the table-frame are glued at their ends and inserted into their positions at the corners 80 of the frame. An adjustable corner-strip, *O*, is placed so as to engage the ends of two adjacent rails, and a clamp, *P*, applied, the one jaw engaging the corner-strip *O* and the other jaw engaging the corner-block *F*, and the 85 hand-screw connecting the jaws is operated until the corner is brought into position.

Where the corner-blocks *F* are not notched before insertion, but present the configuration of *F'*, the notches may be cut and the ends of 90 the rails trimmed and made to coincide with and form a part of the notch after the frame is removed from the former, and I prefer this mode of construction of the table-frame. But if the notches are cut in the corner-blocks before insertion into the former and the ends of 95 the rails be carefully adjusted, then the legs *K* may be placed in position and secured by the bolts *L* while in the former. A stop, *e*, may be secured to the brace *E* to facilitate the adjustment of the rails of the frame in the former. After the glue-joint is made, screws may be in- 100

serted to more firmly secure the rails of the frame to the corner-blocks.

In the construction shown in Figs. 5, 6, 7, 8, the base heretofore described is divided into four sections, each section composed of two arms and the standards A B', A B, A' B, and A' B', respectively. These sections rest on and operate on the sub-base formed of the rails C D, and are secured to them by the bolts *t* passing through the holes O in the sections, which bolts travel in the slots formed in the rails C D. The rails C, on a portion of their upper sides, are guttered, forming ways, in which the arms C' of the sections traverse, (see Fig. 6,) and the rails D on a portion of their upper sides are also guttered, so as to form ways in which the arms D' travel. A portion of the under side of the rail C commensurate with the limit of travel or spread of the rails D is gained out (see Fig. 7) or taken away, and rests upon and travels on those portions of the upper faces of the rails D which have also a portion commensurate with the spread or limit of travel of the rails C gained out or taken away. Slots are provided extending from end to end of the gained-out portions of said rails C and D, within which slots the bolts *t* travel, and said bolts secure the respective sections of the sub-base onto the rails C D, forming said sub-base, and hold said rails in contact with each other.

The operation is as follows: I first set one of the sections square and true with the rails C D, and then adjust the adjacent section to the position required for that dimension of the table-frame, and secure it there by means of the bolt T. I then move and adjust the other rail of the sub-base, which carries the other two sections until they are in the position required for the other dimension of the table-frame, and secure them in position in like manner, when the former is ready for use, as described in the first instance. With this construction the relative positions may be varied to any degree desired, thereby serving as a table-frame

former for a frame having any relative dimensions.

Having thus described my invention, what I claim as new, and desire to secure by Letters Patent, is—

1. A table-frame former in which the respective planes of the interior faces of two adjacent sides are respectively at obtuse angles with the plane of the base, in combination with an adjustable compensating wedge-piece forming part of the sides of the former and the cross-braces, substantially as and for the purpose set forth. 50

2. An adjustable table-frame former composed of four sections, each section comprising a base formed of two arms secured at right angles to each other, each arm carrying a standard or a portion of the sides of the former, and said arms operating in ways formed in the upper surfaces of the rails of the sub-base, and each pair of rails of said sub-base operating longitudinally on each other in gained-out portions therein, and each of said sections secured to the sub-base by bolts which travel in slots formed in the rails of the 70 sub-base, and through the intersecting ends of said arms, substantially as and for the purpose as set forth. 60

3. An adjustable table-former composed of four sections, each section comprising a base 75 formed of two arms secured at right angles to each other, and connected by a brace having a stop, each arm carrying a standard or a portion of the side of the former, substantially as shown and described. 80

4. In a former for frames substantially such as herein described, the combination of the rails G H and I J with the corner-block F, hand-clamp P, and corner-strip O, as and for the purpose set forth.

JACOB A. CONOVER.
